DESIGN FOR A LINOLEUM OR SIMILAR ARTICLE

William Lynen, Woodhaven, N. Y., assignor to BonaFide Mills, Inc., New York, N. Y., a corporation of Maine

Application April 14, 1942, Serial No. 106,572

Term of patent 7 years

To all whom it may concern:

Be it known that I, William Lynen, a citizen of the United States and a resident of Woodhaven, in the county of Queens and State of New York, have invented a new, original, and ornamental Design for a Linoleum or Similar Article, of which the following is a specification, reference being had to the accompanying drawing, forming part thereof, in which—

The figure is a plan view of a section of linoleum showing a complete unit of my design.

I claim:

The ornamental design for a linoleum or similar article, substantially as shown.

WILLIAM LYNEN.
